CLAIM

The ornamental design for a tumbler, as shown and described.

DESCRIPTION

FIG. 1 is a first perspective view of a tumbler, according to my new design;

FIG. 2 is a second perspective view of FIG. 1;

FIG. 3 is an exploded view of FIG. 1;

FIG. 4 is a first perspective view of the top portion of the tumbler, shown separately for ease of illustration;

FIG. 5 is a second perspective view FIG. 4;

FIG. 6 is a front view of FIG. 4;

FIG. 7 is a rear view of FIG. 4;

FIG. 8 is a right side view of FIG. 4;

FIG. 9 is a left side view of FIG. 4;

FIG. 10 is a top plan view of FIG. 4;

FIG. 11 is a bottom plan view of FIG. 4;

FIG. 12 is a perspective view of the bottom portion of the tumbler, shown separately for ease of illustration;

FIG. 13 is a second perspective view of FIG. 12;

FIG. 14 is a front view of FIG. 12, the rear, left, and right views being identical;

FIG. 15 is a top plan view of FIG. 12; and,

FIG. 16 is a bottom plan view of FIG. 12.

The broken lines in the drawings depict portions of the tumbler that form no part of the claimed design.

1 Claim, 16 Drawing Sheets
